UNITED STATES PATENT OFFICE.

WILLIAM C. CARTER, OF ST. LOUIS, MISSOURI, ASSIGNOR TO CARTER CARBURETOR COMPANY, OF ST. LOUIS, MISSOURI, A CORPORATION OF MISSOURI.

CARBURETER.

1,207,134.

Specification of Letters Patent.

Patented Dec. 5, 1916.

Application filed March 16, 1914. Serial No. 825,129.

To all whom it may concern:

Be it known that I, WILLIAM C. CARTER, a citizen of the United States, residing at St. Louis, Missouri, have invented a certain new and useful Improvement in Carbureters, of which the following is a full, clear, and exact description, such as will enable others skilled in the art to which it appertains to make and use the same.

10 This invention relates to carbureters for internal combustion engines, and particularly to carbureters of the type that are not equipped with a spring-actuated air valve which opens automatically when the engine 15 is in operation so as to admit variable quantities of air to the carbureting chamber as the speed of the engine varies.

One object of my present invention is to provide a carbureter of simple construction 20 that is economical in the consumption of fuel, and which will produce an efficient mixture for starting and for all speeds of the engine.

Another object is to provide a carbureter 25 of novel design in which the throttle valve serves as a regulating valve for a port or ports from which liquid fuel is drawn into the intake pipe of the engine at a point in proximity to the throttle valve when the 30 engine is first started and when it is running idle, and at low engine speeds.

Another object is to provide a carbureter which is so designed that a quantity of liquid fuel cannot collect in such a position 35 when the throttle valve is wide open that it will be sucked into the intake pipe and thus strangle the engine, due to an excessively rich charge when the throttle valve is thereafter moved toward its closed position so 40 as to decrease the speed of the engine.

Another object is to provide a carbureter which is so designed that a hot air supply pipe of any preferred length can be combined with the air intake of the carbureter 45 without removing or changing the adjustment of the liquid-fuel-supplying device. And still another object is to provide a carbureter which is equipped with an air-choking device of novel design that facilitates 50 easy starting and which can also be used to govern or regulate the quantity of air that is drawn into the mixing chamber when the engine is in operation.

Other objects and desirable features of my invention will be hereinafter pointed out.

Figure 1 of the drawings is a vertical sectional view of a carbureter constructed in accordance with my invention; Fig. 2 is a horizontal sectional view taken on the line 2—2 of Fig. 1; and Fig. 3 is a vertical sectional view illustrating a slight modification of my invention.

Referring to Fig. 1 of the drawings which illustrate the preferred form of my invention, A designates the float chamber, B designates the liquid-fuel-supplying nozzle, C designates the air inlet to the air chamber or passageway D of the carbureter, and E designates the throttle valve, which is preferably arranged inside of an open-ended tubular-shaped member 1 that forms a mixing chamber, and whose lower end portion projects downwardly into the main air chamber or passageway D of the carbureter. The nozzle B is preferably hollow, and is provided at its upper end with a restricted orifice 2. Adjacent the lower end of said nozzle are ducts 3 that establish communication between the interior of the nozzle and an annular accelerating reservoir F that surrounds the lower portion of the nozzle, the liquid fuel being supplied to the nozzle B through a supply port 4 in the lower end of same which communicates with a duct 5 that leads from the float tank, as shown clearly in Fig. 1. Air ports 6 are formed in the upper portion of the accelerating reservoir F so as to establish communication between said accelerating reservoir and the air chamber D of the carbureter, and the reduced upper end portion of the nozzle B, in which the jet or orifice 2 is formed, projects upwardly into a tubular-shaped air passageway G that is preferably formed by a member open at its upper end and arranged in axial alignment with the mixing chamber of the carbureter, said air passageway G being provided adjacent its lower end with side air inlet ports 7 that establish communication between the lower end of said passageway and the air chamber D of the carbureter.

A starting reservoir H, which is arranged at one side of the accelerating reservoir F, receives liquid fuel from said accelerating

reservoir through one or more ports 8, the upper end of said starting reservoir being open and in direct communication with the air chamber D of the carbureter. A conduit 5 or pipe 9 whose lower end projects into the starting reservoir and terminates above the bottom of same, leads to an annular chamber 10 that surrounds the open-ended, tubular-shaped member 1 in which the 10 throttle valve is arranged, and said member 1 is provided with one or more ports 11 which are so arranged that the throttle valve E will act as a controlling valve which regulates the flow of the liquid fuel from the 15 port or ports 11, as hereinafter described. In the carbureter herein shown a single port 11 is formed in the member 1 at such a point that the throttle valve E will extend transversely across said port intermediate 20 the top and bottom edges of same when the throttle valve is in its closed position, as shown in Fig. 1, said port 11 being of greater cross-sectional area than the thickness of the throttle valve and preferably 25 so positioned that only a very slight portion of same extends above the throttle valve when the throttle valve is closed, thereby causing the major portion of said port to be subjected to atmospheric pressure. In 30 practice the port 11 is so proportioned that just enough fuel will be drawn into the chamber 10 when the throttle valve is closed to start the engine and keep it in operation when it is running idle. The suction 35 that is created above the throttle valve when the engine is cranked with the throttle valve in the position shown in Fig. 1 causes liquid fuel to be sucked up out of the starting reservoir H through the pipe 9 into the 40 annular chamber 10, and thence through the upper edge portion of the port 11 into the intake pipe of the engine. In view of the fact that the lower edge portion of the port 11 is uncovered or subjected to atmospheric 45 pressure at this time air will flow from the mixing chamber through the lower edge portion of the port 11 into the annular chamber 10 when the engine is cranked, and thus combine with the liquid fuel in said 50 chamber to form a rich starting charge that is drawn into the intake pipe above the throttle valve. Opening the throttle valve E increases the area of the port 11 that is subjected to the direct suction in the intake 55 pipe and thus automatically increases the supply of fuel that is drawn into the chamber 10 from the starting reservoir H, the carbureter being preferably so designed that the port 11 constitutes the sole fuel 60 supply up to about one-third of the maximum speed of the engine. The port 11 is preferably arranged comparatively close to the axis of oscillation of the throttle valve E so that the area of said port which is subjected 65 to the action of the suction in the

intake pipe will be increased only gradually, and said port 11 is preferably formed in the wall of the member 1 at such an angle that the fuel will emerge from said port tangentially into the intake pipe and thus 70 travel upwardly through the intake pipe in a spiral path, thereby eliminating the tendency of the charge to hug one side of the intake pipe and to flow to only one pair or group of cylinders of the engine. 75

When the throttle valve E has been opened to such a point that the port 11 is entirely uncovered the suction in the vertically-disposed air passageway G is sufficient to suck liquid fuel out of the orifice 2 80 at the upper end of the fuel nozzle B, the side ports 7 at the lower end of the air passageway G causing the air in the air chamber D of the carbureter to rush into the lower end of the air passageway G at a number of points in proximity to the upper end of the fuel nozzle, as shown in Fig. 1, and thus create sufficient suction on the orifice 2 of said nozzle to lower the level of the liquid fuel in the accelerating reservoir F. 90 When the engine has attained sufficient speed to consume all of the liquid fuel in the accelerating reservoir; or, in other words, after the accelerating reservoir has been sucked dry, the air in the air chamber 95 D of the carbureter is sucked down into said accelerating reservoir through the ports 6 at the upper end of same, and thence into the nozzle B through the ports 3 at the lower end of said nozzle which communicate 100 with the accelerating reservoir, thus breaking the suction on the fuel supply port 4 at the lower end of the nozzle and preventing the excessive flow of fuel from the discharge orifice 2 at the upper end of the nozzle B. 105 When the speed of the engine decreases, due to an excessive load or partial closing of the throttle valve E, the suction on the nozzle, of course, becomes less and consequently the liquid fuel will start to flow into the accelerating reservoir F and cut off the supply of air through the ports 3 in the lower end of the nozzle, the fuel continuing to rise in the accelerating reservoir and eventually filling the starting reservoir H, thereby 115 maintaining a sufficient supply of fuel for the tube 9 when the throttle valve E has been returned to such a position that it partly closes the port 11.

The port 4, through which the liquid fuel 120 is supplied to the nozzle B, is so designed that it will supply a relatively great quantity of fuel at slow engine speeds, and in order to prevent the supply of fuel from the nozzle from increasing proportionately 125 with the speed of the engine, I have designed the carbureter in such a manner that the nozzle will not supply proportionately the same quantity of liquid fuel at high speeds that it does at slow speeds of the engine. 130

In the form of my invention illustrated in Fig. 1 this is accomplished by a device which creates a variable suction in the upper portion of the float chamber A so as to retard the flow of the liquid fuel from the float chamber through the fuel-supply port 4. In the form of my invention shown in Fig. 3 this is accomplished by providing the nozzle of the carbureter with means whereby the carbureter were not provided with a breather-pipe or other air passageway for establishing communication between the upper portion of the float chamber and the air chamber D of the carbureter it would be necessary to substitute a nozzle provided with a different-sized fuel supply port if a hot air supply pipe were attached to the air inlet C of the carbureter on account of the fact that greater suction would be required to draw air through such a pipe than if the carbureter were not provided with same. Likewise, if the length of this hot air supply pipe should be varied it would be necessary to vary the size of the fuel supply port of the nozzle so as to insure the proper supply of fuel from the nozzle according to the suction in the carbureter. In the carbureter shown in Fig. 1, however, it is not necessary to change the nozzle when a hot air supply is attached to the air intake of the carbureter or when the length of the hot air supply pipe is varied, owing to the fact that any increase in the suction in the air chamber D of the carbureter produces a corresponding increase in the suction in the float chamber A, and consequently retards the flow of the fuel through the supply port 4, more or less, according to the intensity of the suction above the level of the fuel in the float chamber. Another desirable feature that results from such a construction is that the fumes from the float chamber pass directly into the carbureter and are thus utilized instead of being wasted as in the carbureters now in general use in which the float chamber has an air vent through which the fumes escape to the atmosphere.

In the form of my invention shown in Fig. 3 the breather-pipe or air passageway I between the upper portion of the float chamber and the air chamber of the carbureter is omitted, and the nozzle B' is provided with a number of ports 3^a located at different horizontal levels so that more or less air will be drawn into the nozzle according to the level of the fuel in the accelerating reservoir F. The quantity of air that enters the nozzle through the ports 3^a increases progressively as the level of the fuel in the accelerating reservoir drops or as the suction in the air passageway G of the carbureter increases so that by the time the engine is running fast enough to suck the fuel directly out of the supply port 4 and up through the nozzle B air will be rushing into the nozzle through all of the side ports 3^a in same and consequently will prevent an excessive flow of fuel from the supply port 4 of the nozzle. When the speed of the engine diminishes the fuel starts to flow into the accelerating reservoir and rise in same progressively as the speed of the engine decreases so that by the time the engine is traveling at slow speed the acceleration of the engine is reduced and the fuel supply to the nozzle is reduced.

At slow engine speeds, or when there is a comparatively low suction in the air chamber D of the carbureter and in the upper portion of the float chamber A, the fuel flows freely from the fuel-supply port 4 that establishes communication between the fuel nozzle and the float chamber. By constructing the carbureter in this manner, namely, providing it with a breather-pipe I for creating a variable suction in the upper portion of the float chamber, I am able to attach a hot air supply pipe of any desired length to the air intake C of the carbureter without changing the adjustment of the fuel-supplying device of the carbureter. If

erating reservoir will be completely filled, thus cutting off the supply of air to the interior of the nozzle.

A choking-valve J is preferably provided for cutting off direct communication between the mixing chamber and the air chamber D of the carburetor when the engine is cranked, and in the preferred form of my invention as herein shown, said choking-valve consists of a horizontally-disposed flange on the upper end of a sleeve 12 that is adjustably mounted in the vertical passageway G of the carburetor into which the upper end of the nozzle B projects. Said sleeve 12 is adapted to be moved upwardly prior to cranking the engine so as to force the choking-valve J against the lower end of the member 1 and thus cut off direct communication between the mixing chamber and the air chamber D of the carburetor. In the embodiment of my invention herein shown the means for raising and lowering the sleeve 12 consists of a horizontally-disposed pinion shaft 13 that meshes with rack teeth 14 on the sleeve 12, said pinion shaft being provided with an adjusting arm 15 which is operatively connected to an adjusting mechanism, not shown, such, for example, as is usually employed on the dash or steering column of an automobile for regulating the carburetor. The choking-valve J not only serves to choke the supply of air to the mixing chamber of the carburetor when the engine is being started, but it also serves to regulate the supply of air to the mixing chamber when the engine is in operation, owing to the fact that the air that is drawn directly into the mixing chamber from the air chamber of the carburetor passes between the lower edge of the tubular member 1 and the choking-valve J. It will, of course, be understood that when the engine is in operation the choking-valve J is spaced away from the lower end of the member 1 that constitutes the mixing chamber of the carburetor, and that said choking-valve remains stationary or at rest while the engine continues in operation. If, on account of atmospheric conditions, it is desirable to vary the supply of air to the mixing chamber, this can be accomplished by merely shifting the choking-valve J slightly so as to vary the size of the space between said valve at the lower edge of the member 1 through which the air passes directly into the mixing chamber.

The specific details of construction of the carburetor are immaterial so far as my broad idea is concerned, but I prefer to construct the carburetor in the manner herein illustrated on account of its simplicity and low cost of manufacture. It consists of a casting x provided at its upper end with a flange 16 for connecting the carburetor to the intake pipe of the engine and a cast-

ing y that forms the bottom of the float chamber A and which is secured to the casting x by a nut 17 that bears against the under side of the casting y and which is screwed into the lower end of the casting x so as to clamp a shoulder 18 on the casting x tightly against the top face of the casting y, said nut and the portion of the casting x into which said nut is screwed being provided with alining ports 5^a through 75 which the fuel flows from the duct 5 of the float chamber to the supply port 4 of the nozzle. The tubular-shaped member that forms the air passageway G, fits snugly in a tubular-shaped portion 19 of the casting x and is permanently connected thereto in some suitable manner as, for example, by expanding or pressing the part 20 of the member G outwardly into a recess in the inner face of the tubular-shaped part 19 of the casting x, as shown in Fig. 1. The nozzle B is screwed upwardly through the nut 17 so that a tapered shoulder adjacent the upper end of said nozzle will be clamped tightly against the edge of a flange 21 on the inner side of the member G through which the reduced upper end portion of the nozzle projects, thereby preventing air or fuel from escaping from the accelerating reservoir into the air passageway G. The sleeve 12 which carries the choking-valve J is telescoped in the upper end portion of the member G and the horizontally-disposed pinion shaft 13 which forms part of the mechanism for adjusting the choking-valve, is journaled in the casting x. The float chamber A can be provided with any suitable kind of mechanism for maintaining a constant level of liquid fuel in said float chamber, and said float chamber may be formed in various ways without departing from the spirit of my invention, but in the form of my invention shown in Fig. 1 it is essential that the float chamber be provided at its upper end with an opening 22 that communicates with the breather-pipe I or that it be designed in such a manner that direct communication is established between the upper portion of the float chamber and the air chamber D of the carburetor.

A carburetor of the construction above-described is economical in the consumption of fuel and produces an efficient mixture for starting and for all speeds of the engine, owing to the fact that the throttle valve accurately regulates and varies the quantity of fuel that is supplied to the intake pipe of the engine above the throttle valve when the engine is started and when it is running idle and at slow engine speeds, the movement of the throttle valve toward its open position causing the supply of fuel from the port 11 to be increased automatically, and the movement of said valve toward its closed position causing the supply from said

port to be decreased automatically. The choking-valve J not only facilitates easy starting of the engine but it also enables the direct supply of air to the mixing chamber 5 to be varied according to atmospheric conditions. By arranging the accelerating reservoir and the fuel supply ports 3 and 4 of the nozzle below the normal level of the liquid fuel in the float chamber and making 10 said ports of sufficient capacity or size to supply a relatively great quantity of fuel at slow engine speeds, gravity causes the fuel to build up in the accelerating reservoir automatically when the speed of the engine 15 diminishes. The variable suction that is created in the upper portion of the float chamber by the breather-pipe I prevents the port 4 from supplying proportionately the same quantity of liquid fuel at high 20 speed that it does at slow speeds of the engine, and furthermore, enables a hot air supply pipe of any desired length to be attached to the air intake C of the carbureter without changing the adjustment of the 25 fuel-supplying device of the carbureter or substituting a nozzle provided with a different-sized supply port.

As previously pointed out, the starting reservoir of the carbureter herein described 30 is supplied from the accelerating reservoir instead of from the float chamber of the carbureter. The advantage of such a construction is that a quantity of liquid fuel cannot collect in the starting reservoir or in the 35 pipe 9 when the throttle valve is wide open, or in such a position that there is not sufficient suction in the chamber 10 to lift fuel through the tube 9. Various carbureters have been designed in which a bypass or 40 fuel-supply tube leads around the throttle valve from a source of liquid fuel supply so as to supply fuel to the intake pipe above the throttle valve when the throttle valve is closed, but in all of the prior carbureters of 45 this type with which I am familiar the bypass leads directly from the float chamber. Consequently, when the throttle valve is wide open or in such a position that no suction is exerted on the bypass the liquid fuel 50 builds up in the bypass or rises in same to the normal level of the liquid in the float chamber, and when the throttle valve is thereafter moved toward its closed position the charge of liquid fuel in the bypass 55 rushes into the intake pipe and strangles the engine. In my improved carbureter the bypass or tube 9 receives its supply of liquid fuel from the accelerating reservoir, and as said accelerating reservoir is sucked 60 dry when the throttle valve is wide open it is not possible for liquid fuel to collect in the pipe or bypass 9 when the throttle valve is wide open and thus strangle the engine when the throttle valve is thereafter moved 65 toward its closed position. The carbureter

comprises comparatively few parts; it is of such simple design that it can be manufactured at a low cost and is not apt to get out of order when in use; and it is provided with only one air inlet, namely, the air 70 inlet C.

Having thus described my invention, what I claim as new and desire to secure by Letters Patent is:

1. A carbureter provided with a mixture 75 passageway through which the mixture travels to the intake of the motor, a fuel supply port in the wall of said passageway, and a throttle valve arranged in said passageway in such a manner that one portion 80 of said port will be subjected to atmospheric pressure and the remainder of said port will be subjected to a high suction created by the motor when the throttle valve is nearly closed, or, in other words, set in such a 85 position that only sufficient mixture to keep the motor in operation will travel through said passageway.

2. A carbureter provided with a mixture 90 passageway through which the mixture travels to the intake of the motor, a main air passageway, an accelerating reservoir that communicates with said main air passageway, a starting reservoir that receives its supply of liquid fuel from said accelerating 95 reservoir, a liquid fuel supply duct leading from said starting reservoir and discharging into said mixture passageway, and a throttle valve arranged in said mixture passageway in such a position that one 100 portion of the discharge end of said fuel duct will be subjected to atmospheric pressure and the remainder will be subjected to a high suction when only sufficient mixture to keep the motor in operation is traveling 105 through the mixture passageway.

3. A carbureter provided with a passageway through which the mixture travels to the intake of the engine, a throttle valve for said passageway, and a fuel-supply port 110 extending transversely through the side wall of said passageway adjacent the axis of oscillation of the throttle valve and at such a point that the throttle valve will vary the effective area of said port which is subjected to the suction above the throttle valve 115 when said valve is closed and partly closed.

4. A carbureter provided with a main air passageway, an accelerating reservoir in which the liquid fuel collects at slow engine speeds, said accelerating reservoir communicating with the main air passageway of the carbureter, a starting reservoir formed by a recess or chamber separate and distinct from that constituting the accelerating reservoir and receiving its supply of fuel from said accelerating reservoir, a fuel-supply duct through which the fuel is drawn from said starting reservoir at slow engine speeds, and a nozzle through which 130

the fuel is drawn from said accelerating reservoir at intermediate engine speeds.

5. A carbureter provided with an accelerating reservoir in which the liquid fuel collects at slow engine speeds, a starting reservoir which receives its supply of fuel from said accelerating reservoir, a fuel-supply duct through which the fuel is drawn from said starting reservoir at slow engine speeds, a nozzle through which the fuel is drawn from said accelerating reservoir at intermediate engine speeds, a liquid fuel-supply port for said nozzle of sufficient capacity to supply a relatively great quantity of fuel at slow engine speeds, and means for creating a variable restraining force on the liquid fuel being admitted to said port so as to prevent said port from supplying proportionately the same quantity of fuel at high engine speeds that it does at slow engine speeds.

6. A carbureter provided with an accelerating reservoir in which the liquid fuel collects at slow engine speeds, a starting reservoir which receives its supply of fuel from said accelerating reservoir, a fuel-supply duct through which the fuel is drawn from said starting reservoir at slow engine speeds, a nozzle through which the fuel is drawn from said accelerating reservoir at intermediate engine speeds, a float chamber, a supply port through which the fuel flows from said float chamber to said nozzle, and means for creating a variable suction in the upper portion of said float chamber so as to regulate the flow of fuel from said supply port.

7. A carbureter provided with a main air passageway, an accelerating reservoir communicating with said air passageway, a hollow nozzle in said accelerating reservoir provided at its upper end with a discharge port, means for supplying liquid fuel to said nozzle, means for establishing communication between the interior of said nozzle and said accelerating reservoir, a starting reservoir that receives its supply of fuel from said accelerating reservoir, and means for conducting the fuel from said starting reservoir to the intake pipe of the engine at a point above the throttle valve when the throttle valve is closed or partly closed.

8. A carbureter provided with a main air passageway, an accelerating reservoir communicating with said air passageway, a hollow nozzle in said accelerating reservoir provided at its upper end with a discharge port, means for supplying liquid fuel to said nozzle, means for establishing communication between the interior of said nozzle and said accelerating reservoir, a starting reservoir that receives its supply of fuel from said accelerating reservoir, means for conducting the fuel from said starting reservoir to the intake pipe of the engine at a point above

the throttle valve when the throttle valve is closed or partly closed, said means comprising a port in the throttle valve passageway of the carbureter whose effective area is controlled by the throttle valve, and means for preventing the nozzle from being supplied with proportionately the same quantity of fuel at high engine speeds that it is supplied with at slow engine speeds.

9. A carbureter provided with an air chamber, a vertically-disposed air passageway in said chamber which is open at its upper end, a fuel-supply nozzle at the lower end of said passageway, side ports in the lower end portion of said air passageway through which the air rushes into said passageway and thus exerts suction on said nozzle, and an accelerating reservoir that supplies fuel to said nozzle and whose upper end communicates with the air chamber of the carbureter.

10. A carbureter provided with an air chamber, a vertically-disposed air passageway in said chamber which is open at its upper end, a fuel-supply nozzle at the lower end of said passageway, side ports in the lower end portion of said air passageway through which the air rushes into said passageway and thus exerts suction on said nozzle, an annular accelerating reservoir surrounding the lower portion of said nozzle and provided with an opening that establishes communication between said reservoir and the air chamber of the carbureter, a fuel-supply port at the lower end of said nozzle, and means for establishing communication between the interior of said nozzle and said accelerating reservoir.

11. A carbureter provided with an air chamber, a vertically-disposed air passageway in said chamber which is open at its upper end, a fuel-supply nozzle at the lower end of said passageway, side ports in the lower end portion of said air passageway through which the air rushes into said passageway and thus exerts suction on said nozzle, an annular accelerating reservoir surrounding the lower portion of said nozzle and provided with an opening that establishes communication between said reservoir and the air chamber of the carbureter, a fuel-supply port at the lower end of said nozzle, means for establishing communication between the interior of said nozzle and said accelerating reservoir, a starting reservoir in which the liquid fuel collects when the engine is running idle, and a conduit leading from said starting reservoir to a point above the throttle valve of the carbureter.

12. A carbureter provided with an air chamber, a mixing chamber that is normally in direct communication with said air chamber, a throttle valve for governing the flow of the mixture from said mixing chamber.

and a choking-valve separate and distinct from the throttle valve for cutting off direct communication between said air chamber and mixing chamber to facilitate easy starting of the engine, said choking-valve being stationary or at rest when the engine is in operation.

13. A carbureter provided with an air chamber, a mixing chamber that is normally in direct communication with said air chamber, a throttle valve for controlling the flow of the mixture from said mixing chamber, and an adjustable device separate and distinct from the throttle valve that serves as a choking-valve for said mixing chamber and which can also be used to govern the supply of air from the air chamber to said mixing chamber.

14. A carbureter provided with an air chamber having a fixed air inlet, a mixing chamber communicating with said air chamber, a vertically-disposed air passageway in said air chamber whose upper end is open and normally in direct communication with said air chamber, a choking device separate and distinct from the throttle valve for cutting off direct communication between the air chamber and said air passageway and mixing chamber, and restricted passageways for establishing indirect communication between said air chamber and mixing chamber when said choking device is operative.

15. A carbureter provided with an air chamber having a fixed air inlet, a mixing chamber communicating with said air chamber, a vertically-disposed air passageway in said air chamber whose upper end is open and normally in direct communication with said air chamber, a choking device for cutting off direct communication between the air chamber and said air passageway and mixing chamber, a fuel-supplying device at the lower end of said air passageway, and side ports in said air passageway adjacent said fuel-supplying device, through which the air passes from said air chamber into said air passageway when said choking device is in position to cut off direct communication between said chamber and passageway.

16. A carbureter provided with an air chamber, a tubular-shaped member having its lower end terminating inside of said air chamber and provided with a throttle valve, and an adjustable device in said air chamber coöperating with the lower end of said tubular shaped member to regulate the flow of

the air from said air chamber into said member.

17. A carbureter provided with an air chamber, a mixing chamber formed by a tubular-shaped member whose lower end terminates inside of said air chamber, a vertically-disposed adjustable sleeve arranged inside of said air chamber and provided at its upper end with a horizontally-disposed flange constituting a choking portion for varying the flow of air into said mixing chamber, a fuel-supplying device terminating inside of said sleeve, and means for causing air to travel upwardly through said sleeve and thus exert suction on said fuel-supplying device.

18. A carbureter provided with an air chamber, a mixing chamber formed by a tubular-shaped member that terminates inside of said air chamber, a vertically-disposed adjustable sleeve arranged inside of said air chamber and provided at its upper end with a portion for varying the flow of air into said mixing chamber, a fuel-supplying device terminating inside of said sleeve, means for causing air to travel upwardly through said sleeve and thus exert suction on said fuel-supplying device, an accelerating reservoir from which said fuel-supplying device receives its supply of fuel at intermediate speeds, a starting reservoir in which liquid fuel collects at slow engine speeds, and a bypass leading from said starting reservoir to a point above the throttle valve of the carbureter.

19. In a carbureter for internal combustion engines, the combination of a mixing chamber, a fuel jet therein, means to supply fuel to the jet, an auxiliary fuel tube for conveying fuel to the mixing chamber, an auxiliary fuel container having means for the supply of fuel thereto, an additional fuel container having restricted connection with said auxiliary fuel container and from which additional fuel container the said auxiliary fuel tube sucks, means for varying the air pressure in both of the said fuel containers during the operation of the carbureter.

In testimony whereof I hereunto affix my signature in the presence of two witnesses, this thirteenth day of March, 1914.

WILLIAM C. CARTER.
